GLOVE

Gladys Whitcomb Geissmann, New York, N. Y.

Application January 6, 1939, Serial No. 249,577

3 Claims. (Cl. 2—169)

This invention relates to improvements in gloves and particularly relates to improvements in blanks for gloves and to thumb constructions therefor.

5 In my Patent No. 2,125,673, granted August 2, 1938, are disclosed glove constructions in which the fingers are formed of portions projecting from palm and back portions. The finger portions may be joined by fourchettes or connecting 10 tapes that extend over the ends of the fingers or otherwise spaced to a substantial degree the front and back portions to provide a third dimensional effect. The thumb portions of the gloves likewise are of substantially three dimensions and 15 because of the use of the strip conforming to the shape of the thumb and taper of the forefinger that extends from the end of the thumb along the outer edges of the forefinger portion, the thumbs are free of cross seams and are 20 thereby rendered extremely flexible. Inasmuch, however, as the thumb and forefinger strips are elongated and of peculiar shape, they are difficult to cut and there is a problem of a possible waste of material in their cutting.

25 An object of the present invention is to provide well fitting gloves in which the thumb front is formed integrally with the palm and back portions whereby waste of material is greatly reduced.

30 Another object of the invention is to provide gloves in which the thumb front portions are formed from material that is normally removed to provide an aperture or recess for receiving the thumb back and front.

35 Another object of the invention is to provide gloves and glove blanks having integral properly shaped or anatomically correct thumb front tabs, thereby eliminating cross and longitudinally extending seams and at the same time providing 40 a flexible properly fitting and located thumb.

Other objects of the invention will become apparent from the description of a typical form of glove embodying the invention set forth hereinafter.

45 Gloves and glove blanks embodying the invention are characterized by integral palm, finger, and a reversely curved or generally S-shaped thumb front portion which is formed in a recess in the palm portion and turns upwardly and across the palm portion when attached to the back portion of the thumb. The back portion of the thumb is connected to the palm portion of the glove along the edges of the recess and the thumb front to form a pocket

conforming to the shape and disposition of the normal human thumb.

More particularly, the glove blank is formed from a single sheet of material, such as, for example, leather or fabric and is formed, preferably, with the forefinger portions disposed substantially centrally of the blank and connected by a web of substantial width, that is, slightly less than the thickness of the normal human finger. The palm portion of the blank is considerably narrower than the back portion because a portion thereof is cut away in order to provide the recess for receiving the thumb back portion. The edge of the palm portion is formed on a line extending for the major portion of its length 10 substantially longitudinally of the palm and at its inner end curving on a wide arc to a point substantially in alignment with the axis of the forefinger portion. The edge of the back portion of the preferred form of glove adjacent the 15 recess is substantially straight and in alignment with the edge of the forefinger portion of the back. Thus the recess is formed principally in the palm portion of the glove and corresponds in position to the position of the normal human 20 thumb.

The material removed from the glove blank to form the thumb recess normally is wasted but in gloves embodying the present invention a portion of this material is used to form the front 30 of the thumb. The thumb front is an elongated tab joined to the blank at a zone at the end of the curved palm edge, and projects downwardly into the recess. The thumb flap consists of an inner portion inclined at an acute angle across 35 the recess toward the palm portion which merges into a longer portion having a rounded end that is disposed substantially parallel to the edge of the thumb recess or substantially axially or parallel to the axis of the recess.

40 The thumb back portion may be a separate blank consisting of a strip of material having pointed portions or horns projecting from opposite longitudinal edges thereof and a tab having a rounded end which is joined to the thumb front portion. The points or horns fit into the corners of the recess formed between the edge portions of the palm and back portion and the thumb front. When assembled these horns or points provide freedom of action of the thumb by the introduction of a sufficient amount of material to allow the thumb to swing freely in any desired direction.

45 Gloves of the type described generally above 55

may be provided with fourchettes for the middle and little fingers similar to those disclosed in my Patent No. 2,125,673, or those disclosed in my copending application Serial No. 213,956, filed June 16, 1938, or with any other desired type of fourchette. When fourchettes of the type disclosed in my copending application and my Patent No. 2,125,673 are used for connecting the finger portions, glove blanks embodying the present invention may be provided with a tab projecting from the web between the forefinger portions that can be brought over the ends and joined to the ends of the forefinger portion to maintain them in spaced apart relationship and to give them the third dimensional effect. The tab may extend downwardly into the crotch between the forefinger and the adjacent finger or it may be a short tab that extends only part way down the side of the forefinger, the fourchette being completed by a short strip extending into the crotch and connected to the end of the tab by means of a transverse seam.

Gloves of the type described above may be formed of various types of material such as leather or fabrics and provide a novel appearance because of the fact that various types or colors of materials can be used in combinations for the thumb back or fourchette constructions as may be desired. The integral thumb construction eliminates transverse seams in the thumb crotch and also eliminates or reduces the number of seams extending longitudinally of the outer edges of the forefinger portions, while at the same time providing a construction which accurately fits the thumb and allows great freedom of movement thereof.

For a better understanding of the invention reference may be had to the accompanying drawing, in which:

40 Figure 1 is a plan view of a typical form of glove blank embodying the invention;

Figure 2 is a plan view of a typical form of thumb-back portion to be used with the blank shown in Figure 1;

45 Figure 3 is a perspective view of the glove formed from the blanks shown in Figures 1 and 2 with the thumb portion spread out in order to disclose the details of the thumb front; and

Figure 4 is a perspective view of the glove with 50 the thumb portions shown in its normal position and the forefinger portion bent in order to disclose the manner in which the forefinger tab is connected to the fourchette on the forefinger.

The form of glove disclosed in Figures 3 and 4 55 may be formed from a blank of the type disclosed in Figure 1 which consists of a unitary piece of material having a palm portion 10 and a back portion 11. The palm portion 10 is provided with finger portions 12, 13, 14 and 15 and the back portion 11 is provided with corresponding finger portions 12', 13', 14' and 15'. The finger portions 12, 13, 14 and 15 are made slightly longer than the finger portions 12 to 15 inclusive in order to provide room for the fingernails and 60 are separated by a series of slots 16 of greater length than the slots 16 which separate the finger portions 12 to 15 in order to conform to the inclination of the crotches between the fingers. The forefinger portions 12 and 12' are spaced 65 apart by means of a web portion 17 having a tab 17' projecting beyond the ends of the finger portions 12, 12' for a purpose later to be described. A thumb front tab 18 is disposed between the palm portion 10 and the back portion 11 in a recess provided by cutting away por-

tions of the palm and back portion. One edge of the recess is defined by an edge 19 on the palm portion which is substantially straight from the cuff edge 20 of the palm portion to adjacent its upper end where it is curved as shown at 21 5 toward the back portion 11. The edge 19 extends longitudinally of the palm portion and substantially in alignment with the slot 16 between the finger portions 13 and 14. The opposite edge of the recess is defined by an edge portion 22 on the back portion 11 of the glove which is substantially straight from the cuff edge 23 of the back portion to its upper end, the edge 22 being substantially in alignment with the inside of the finger portion 12'. It will be understood that the 15 recess need not extend to the cuff edges 20 and 23 but may be an aperture as shown in dotted lines on the blank. The thumb portion 18 is connected to the palm and back portion along a zone extending from the end of the curved edge 20 21 to the upper end of the edge 22 or substantially midway between the bases of the forefinger portions 12 and 12'. The tab 18 is of reversely curved formation having an upper portion 24 inclined at an acute angle to the axis of the palm 25 portion and curving into a longer portion 25 that is substantially coaxial with the recess between the edges 19 and 22. The portion 25 terminates in a rounded end 26 substantially the shape of the end of the human thumb. As shown in Figures 1 30 and 3, the thumb portion 18 is of a "dog leg" shape and is so formed that when bent upwardly and across the palm portion as illustrated in Figure 4 provides an inclined crotch corresponding to the taper of the crotch between the thumb 35 and forefinger of the human hand.

The back of the thumb is formed from a blank 27 generally of the type disclosed in Figure 2 which has a curved lateral edge portion 28 and an oppositely curved edge portion 29 for providing 40 fullness in the thumb when connected to the edges 19 and 22. At the upper end of the blank 27 is a tab 30 which forms the back of the thumb proper and has a rounded upper end 31 corresponding generally to the curvature of the end 26 45 of the thumb front tab 18. The lateral edge 28 terminates in a point 32 or horn which is adapted to fit in the angle between the thumb portion 18 and the edge 22 of the back portion. The lateral edge 29 likewise terminates in a more curved and longer horn or point 33 which is disposed 50 between the curved edge 21 of the palm portion and the thumb flap or tab 18.

In assembling the glove the thumb back blank 27 is placed in the recess between the thumb and back portion with its lower edge in alignment 55 with the cuff edges 20 and 23 of the palm and back portions and the lateral edge 29 is stitched to the edge 19 of the palm portion up to its juncture with thumb tab 18. Likewise, the lateral edge 28 of the blank 27 is stitched to the edge 22 of the back portion of the blank and the thumb tab 30 is stitched along its edges to the thumb front tab 18 as shown particularly in Figure 3. The finger portions 13, 13', 14, 14', 15, 15' are 60 connected by fourchettes 34 that extend over the ends of the finger in the manner disclosed in my Patent No. 2,125,673, with the finger portions 13', 14', 15' extending outwardly beyond the finger portions 13, 14 and 15 to provide inclined ends on 65 the fingers. The tab 17' is bent over the ends of the finger portions 12, 12' and stitched thereto as shown in Figure 4 in order to space the ends of the finger portions apart and is joined by a transverse seam 35 to a fourchette strip 36 which 70 75

extends downwardly into the crotches between the finger portions 12, 12' and 13, 13'.

The thumb of the glove is formed of two parts, one of which, namely tab 18, is formed integrally with the palm and back portions and the other which is stitched in the recess in the palm portion. There are no seams extending transversely of the thumb front tab 18 and consequently there is nothing to bind movement of the thumb. Also, the shape of the thumb tab 18 is such as to provide an inclined forwardly opening crotch between the thumb and forefinger which provides freedom of movement of the thumb upwardly and downwardly or across the palm of the glove. Likewise, there is no seam around the base of the thumb or thumb muscle which might rip due to stresses exerted thereon by gripping with the thumb, and freedom of movement of this portion of the glove with the thumb is thereby assured. It will be understood that the shape of the thumb front and thumb back can be modified as the purpose demands and that the proportions of these parts may be varied in order to provide a properly fitting glove construction. Therefore, the above described embodiment of the invention should be considered as illustrative and not as limiting the scope of the following claims.

I claim:

1. A glove blank comprising palm and back portions having adjacent integrally connected forefinger portions extending therefrom and spaced apart opposed edges on said palm and back portions forming a recess extending from

the cuff edge of said palm and back portions inwardly toward said forefinger portions, the edge on said back portion being substantially straight throughout the edge on said palm portion being curved at its inner end toward the edge on said back portion and a thumb flap of less width than the width of said recess integral with said palm and back portions, said thumb flap including an inner portion having curved opposite lateral edges extending diagonally across said recess from the inner ends of the edges on the palm and back portions and joined by an oppositely curved portion to a portion having a rounded outer end extending substantially axially of said recess.

2. An integral glove blank comprising integral palm and back portions having adjacent forefinger portions with spaced apart rounded ends and a tab projecting from between the rounded ends of the forefinger portions adapted to be connected to, extend over and maintain the rounded ends in spaced apart relationship.

3. The glove blank set forth in claim 2 in which the palm and back portions include opposed inner edges defining a recess substantially entirely in the palm portion and a thumb front tab having an inner portion extending from the inner end of the recess adjacent inner edge of the back portion toward and at an acute angle to the palm portion and an angularly related outer portion extending substantially axially of said recess and terminating in a rounded end.

GLADYS WHITCOMB GEISSMANN.
